UNITED STATES PATENT OFFICE.

WILLIAM E. CLAYTON, OF BARBERTON, OHIO.

MOISTURE-PROOF CONSTRUCTION.

1,072,310.

Specification of Letters Patent.

Patented Sept. 2, 1913.

Application filed December 6, 1912. Serial No. 735,251.

To all whom it may concern:

Be it known that I, WILLIAM R. CLAYTON, a citizen of the United States, residing at Barberton, in the county of Summit and State of Ohio, have invented certain new and useful Improvements in Moisture-Proof Constructions, of which the following is a specification.

This invention relates to building constructions in general and has for its primary object the production of a construction the walls of which shall be moisture-proof so that the interior of the construction may be kept absolutely dry.

In many constructions such as mausoleums, storage cellars, and the like, it is desirable that moisture be prevented from entering through the walls which are usually made of concrete, cement, stone, or vitreous building blocks, all of which are more or less porous and are incapable of excluding moisture. My present invention contemplates a structure, the walls of which are provided with sheets of impervious material, adapted to preclude the passage of moisture therethrough.

One embodiment of my invention and many of the attendant advantages thereof will be readily understood from the following description when considered in connection with the accompanying drawings throughout the various views of which like reference characters indicate similar parts.

Referring to the drawings—Figure 1 is a fragmentary section of a building construction embodying my invention; Fig. 2 is an enlarged fragmentary sectional view through a corner of one of the walls of the construction; and Fig. 3 is a face view of a fragment of a wall showing one method of closing the joints between the sheets of impervious material.

In Fig. 1 of the drawings I have illustrated a section of a mausoleum comprising the foundation 5, the side walls 6, the roof 7 and the top 8. These walls and roof may and usually are constructed of concrete blocks or poured concrete and within the construction is formed a plurality of crypts 9 usually constructed of the same material and integral with the building walls. In order to preserve the bodies in the crypts it is desirable that they be air-tight and moisture-proof, but it is impossible to secure

these results with walls of ordinary construction, since cement, brick, building blocks, terra cotta, or any other of the well known building materials are more or less porous and moisture will gradually seep through them.

My present invention contemplates incorporating in the structure of the walls sheets of glazed material 10, glass being very well adapted for the purpose, not only because it is impervious but, also, for the reason that cement will adhere thereto very tenaciously thereby producing a uniform, durable and strong structure. The sheets of glazed material may be incorporated within the body of the walls, or, they may be disposed on one surface thereof and any suitable finish may be applied thereover, if desired. The sheets may be of any preferred size and configuration and at the junction of adjacent sheets I prefer to make a moisture-proof joint by cementing or otherwise securing over the joint a strip of glass or other glazed material 11, as shown. Where the sheets of impervious material join at the corners I employ suitable angle pieces 12 of the same material, so that when the construction is completed an absolutely impervious structure is produced. If preferred, the joints between adjacent sheets may be closed by asphaltum or other suitable material, but I have found that the best results are obtained by employing strips of glazed material 11 and 12 of suitable shape and securing these strips over the joints by water-proof cement 13 of suitable character.

While I have shown and described my invention as embodied in a mausoleum, it will be obvious that it may be incorporated in any desired building construction and that the walls of the construction may be made of any suitable building material with the impervious sheets embedded therein or applied thereto in any preferred manner. I do not wish, therefore, to be understood as limiting the invention to a building construction such as that disclosed, but it will be manifest that the structure is capable of variation within wide limits without departing from the essence of the invention as set forth in the following claim.

I claim:

In a moisture-proof construction, the com-

2
bination of a wall body composed of suitable material, sheets of glass arranged with their edges adjacent to each other, said sheets being cemented to the wall body, 5 angle-shaped strips of glass disposed over adjacent edges of the glass sheets in the corners of the structure, flat strips of glass disposed over the adjacent edges of the glass

sheets along the sides of the structure, and water-proof adhesive material joining said 10 glass strips to the glass sheets to form moisture-proof joints therebetween.

WILLIAM R. CLAYTON.
